UNITED STATES PATENT OFFICE.

JAMES T. FENTON, OF SALT LAKE CITY, UTAH.

CONTINUOUS SYSTEM FOR THE TREATMENT OF COAL.

Application filed August 24, 1922. Serial No. 584,039.

To all whom it may concern:

Be it known that I, JAMES T. FENTON, a citizen of the United States, and resident of Salt Lake City, in the county of Salt Lake and State of Utah, have invented certain new and useful Improvements in Continuous Systems for the Treatment of Coal, of which the following is a specification.

My invention relates to apparatus for the treatment of coal for the purpose of removing the volatile constituents therefrom, producing a large amount of gas, and leaving a residue that may be termed synthetic anthracite or long flame coke and which forms a valuable fuel.

A retort of any desired size is provided and the coal is introduced continuously by means of conveyors which may be of the worm type or drag conveyors, or other equivalent mechanism. Within the retort the coal is treated with superheated steam at a relatively low temperature, generally not exceeding 1000° F. This steam distills off the gaseous and volatile elements of the coal, which cause the smoke in the usual combustion thereof, and leaves as a residue a fuel which has a high value and will burn without producing smoke.

The products of the distillation are automatically separated into certain fractions after leaving the retort, and the temperature of each condenser is automatically controlled by means of a thermostat, so that the condensate will require but little purification. The gas is conducted to any form of gas purification apparatus, but in great part will be pure enough to burn without further treatment.

The coal is preheated while passing through the conveyors, and the superheated steam which heats the conveyors by passing through a jacket around the same is finally injected into the conveyor and displaces the air normally indrawn with the coal.

The coal is constantly in movement, and if the retort has a capacity of 200 cubic feet, and the material being treated is pea or nut coal, it will be fed to the retort at the rate of about five cubic feet per minute (seven and one-half tons per hour), and therefore would require about forty minutes to pass through the retort.

The bottom of the retort is supplied with circulating water which cools the product

before its exit and also forms a seal. The coal may be withdrawn by means of a worm conveyor and carried away in any desired manner. Instead of steam, some other inert gases may be used which can be heated to the desired temperature, but steam is preferable since the particles thereof tend to carry over the distillate in suspension.

There is no destructive distillation of the coal, since there is no combustion thereof. The material does not reach fusion temperature but the material is kept in a constant state of agitation and reaches a semi-fluid condition.

This apparatus can be used to treat any kind of coal, such as lignites, bituminous, and cannel coal. It can also be used for the purpose of treating oil sands, oil shales, and any kind of oil bearing solids, although of course in such cases the material after treatment will not serve as a fuel.

Further objects of the invention will be apparent from the following detailed description and the appended claims.

In the drawings:

Figure 1 is a diagrammatic view, partly in section, of the system of apparatus forming the subject matter of my invention.

Figure 2 is a modification showing a different form of conveyor for delivering coal to the retort, and also a modified form of blower.

Figure 3 is a cross section taken on the line 3—3 of Figure 2 and showing the cleaning jets.

Figure 4 is a vertical section of a retort shown in more detail than in Figure 1.

Figure 5 is a vertical section taken on the line 5—5 of Figure 4.

Figure 6 is a side view of a portion of the retort.

Figure 7 is a sectional view on the line 7—7 of Figure 1.

Figure 8 is a similar sectional view on the line 8—8 of Figure 1.

Figure 9 is a side view, partly in section, on the line 9—9 of Figure 1, of one of the automatic condensers.

Figure 10 is a top plan view of the same.

Figure 11 is a plan view of a detail.

Referring to Figure 1, there are illustrated two preheating conveyors 1 and 2 of the worm type. The spindles of the worms extend outside of the casings and are

provided with pulleys 3 and 4 connected by a belt 5, power being communicated thereto in any desired manner. A casing 6 entirely or partially surrounds the conveyors and 5 has a branch 7 opening into the conveyor casing 1 at or near the point 8 of entry of the coal. Superheated steam at a relatively low pressure is conducted to the casing 6 by a pipe 9 controlled by a valve 10. The 10 steam serves the purpose of preheating the coal in the conveyors and finally is injected into the coal to displace any air that is drawn in. It is to be noted that the flow of steam through the preheating casing is 15 in the opposite direction to the movement of the coal itself. After passing through the conveyors the coal is admitted into a blower 11 with the end of which communicates a pipe 12 controlled by a valve 13 through which is introduced superheated steam under a relatively high pressure to force the coal into the retort. This blower is in communication with the retort 14 and has its inner end located within the retort 20 and provided with baffle 15 against which the coal is blown by the steam.

One or both of the conveyors may be a drag conveyor such as illustrated in Figure 2 and subsequently described. This type 30 of conveyor is illustrated in said figure as used with a different form of blower, but it is to be understood that either conveyor may be used with either form of blower and that other modifications of each may be 35 employed without departing from the spirit of the invention.

As illustrated in Figure 2, the drag conveyor comprises a casing having a central section 16 and two end sections 17 and 18. 40 In the section 17 is firmly mounted the axle of a sprocket wheel 19, while in the section 18 the axle of a sprocket wheel 20 is movably mounted. An endless belt 21 passes around wheels 19 and 20 and carries drag 45 elements 22 which carry the coal along. An entrance chute 23 is provided for the coal. A steam jacket 24 is provided for only the middle section 16 whereby the shafts and 50 wheels will not be so highly heated. Making the casing in sections also facilitates easy repair by moving either or both end sections.

The ends of the axle of the sprocket 20 are fixed in sliding bearings and an extension 55 passes through air tight packings to the outside of the casing and then through a bracket 26. A large nut or handwheel 27 is screw threaded on the extension 25 and a spring 28 is interposed between the handwheel and the bracket 26. In this manner the belt or apron 21 may be kept tensioned, and may be adjusted as desired. However, it will be permitted to yield under any sudden shock and moreover the spring 60 mounting for one end permits the tension

to be maintained through varying temperatures with their accompanying changes in length of the apron.

From the steam jacket 24 a jet 29 injects steam into the conveyor at the entrance 70 chute 23. The jacket is supplied with superheated steam from a pipe 30 provided with a valve 31 and connected to a main steam pipe 32. As particularly shown in Figure 75 3, branches 33 and 34 lead from the steam pipe 30 and terminate in jet nozzles downwardly and inwardly directed upon the belt and drag elements or scrapers 22. When certain types of material are undergoing treatment it becomes sticky, and tends to 80 clog the conveyor. These steam jets serve to clean the scraper blades, and are also placed just above the feed chute 35 and therefore tend to force the material into and through said chute.

The feed chute discharges into the blower 36 which in this form is angularly inclined and leads into the retort 14. It has a baffle 15' at its inner end. A pipe 37, provided with a valve 38, connects with the superheated steam pipe 32. By inclining the blower, larger pieces of coal can be handled with less trouble and with less pressure of the steam.

The retort is described with especial reference to Figures 4, 5 and 6, since Figure 1 is intended to be diagrammatic and does not disclose all of the details. The retort is preferably formed in sections, a top section 39, intermediate sections 40, 41 and 42, and a bottom section 43. This permits more ready repair when any portion of the retort is broken or worn, and furthermore, a plurality of the plain sections 40 can be used when it is desired to increase 105 the size of the retort.

Sections 41 and 42 are provided with two fins 44 on each side of the interior, and underlying these fins are steam pipes 45 which pass through the section walls and communicate with a main steam pipe 46. These pipes have perforations upwardly directed so that the steam which is admitted under pressure has an upward and inward direction as indicated in Figure 4. These sections also support a combined fin and pipe 47 preferably made in one piece, each section having one of these centrally placed. The exit openings in these pipes are on both sides and upwardly and outwardly directed 110 as indicated. In this manner the superheated steam is forced into intimate contact with all parts of the material passing through the retort.

Mounted in section 42 are two mechanical 125 agitators comprising rotating shafts provided with projecting arms as clearly illustrated. In the section 43 is a larger agitator 49 of similar type but located in the center of the retort. The shafts of the agi- 130

tators 48 extend through the retort and have bevel gears 50 at their outer ends which mesh with bevel gears 51 on a shaft 52. These bevel gears 51 are reversely arranged

5 so that the agitators will rotate in reverse directions. The shaft of the agitator 49 is also provided at its outer end with a bevel gear 53 which meshes with a bevel gear 54 on a shaft 55. The outer end of the shaft 10 52 is provided with a bevel gear 56 and the outer end of the shaft 55 with a bevel gear 57 which mesh with bevel gears 58 and 59 respectively on a power shaft 60 driven in any desired manner.

15 Also mounted in the section 43 are two withdrawal cylinders 61 to be more fully described later, and their axles are provided at the ends outside the retort with worm gears 62 meshing with worms 63 on a shaft 64 provided at one end with a bevel gear 65 meshing with a bevel gear 66 on the power shaft 60. Inside this bottom section 43 is a casing 67 that directs the coal or other material upon the withdrawal cylinders and when discharged therefrom, upon the worm conveyor in the lower part thereof. The outside of the cylinders fit close to the casing 67 so that the two act as crushers. If desired the ends of the cylinders, as well as the ends of the agitators may be carried by flange plates bolted to the outside of the retorts, so that they can be removed bodily by removal of the flange bolts. Fitted above the cylinders is an apron 68 which will direct the 35 material thereon and also retard the movement thereof.

Above the withdrawal cylinders, on each side of the retort, is a water pipe 69 to direct water downward. Also the lower part of 40 the retort is kept filled with water, forming a water seal. This water may be received from any suitable source and is preferably under constant circulation. In the lower section of the retort is a worm conveyor 70 extending upwardly and outwardly and whose outer end is above the level of the water within the retort. The coal is removed after treatment by this conveyor, which may be of the drag type if desired, and dumped upon a belt or other conveyor 71 diagrammatically indicated in Figure 1.

The upper section of the retort may be provided with a plurality of openings 72 for the insertion of the blower, those not in use 55 of course being appropriately closed. From the top section also leads off the exit pipe 73 for the vapors and gas produced by the distillation. This outlet pipe has within it a steam jet pipe 74 controlled by a valve 75 for the admission of superheated steam. This not only carries the vapors through into the cracking chamber but may also serve to additionally crack some of the products of distillation. If desired a thermostat 76 may be placed in the outlet pipe 73 and

control the valve 75, thus regulating admission of superheated steam and providing that the vapors leaving the retort shall have substantially a constant temperature.

The pipe 73 extends a considerable distance into the cracking chamber 77 and the combined steam and vapors strike against a baffle plate 78 with great force. From the cracking chamber the vapors pass through a pipe 79 into a separator tank 80 shown in detail in Figures 7 and 8. It will be noted that the vapors enter the tank 80 at the side and are thereby given a centrifugal or rotary motion. This causes the precipitation of the higher pitches that may not have been cracked, and of any solid particles that may have been carried over by the steam and vapors. Furthermore, in the treatment of oil sands, shales, or coals containing considerable sulphur, this tank may be maintained at such a temperature that the sulphur will be in a liquid state and thus will be separated from the vapors that pass into the condenser system. In this manner the vapors that are to be condensed in this system will be practically free from sulphur.

In this condenser or separator tank is placed a steam coil 81 connected through a pipe controlled by a valve 82 with a main superheated steam supply pipe 83. The valve 82 is controlled by a thermostat 84 at the top of the vapor outlet 85 which comprises four columns connected at their top by a chamber 86 in which is placed the thermostat.

If the type of material being treated or the products desired require it, the superheated steam coil 81 may be connected to a normal steam line or even to a cold water pipe. In the majority of cases however, the superheated steam will be required.

From the separator tank the vapors pass through the pipes 85 to the first of four condenser chambers 87, 88, 89 and 90, the first three of which are substantially identical in construction. From the chamber 86 to which the four pipes 85 connect, four other pipes 91 pass downward to the chamber 87 and enter the same on one side of a baffle 92 around which the vapors pass to exit pipes 93 similar to the pipes 85. A perforated steam pipe 94 is located in the chamber 87 connected to the main steam line 83 by a pipe controlled by a valve 95. This valve is controlled by a thermostat 96 at the top of the pipes 93.

In similar fashion valves 97 and 98 which regulate admission of steam to the chambers 88 and 89 are controlled by thermostats 99 and 100 respectively. The last chamber 90 is provided with a pipe for supplying cold water to a coil 101 from which it passes up into a cooling tank 102 which surrounds the inlet and outlet pipes to this chamber. From this chamber the gas is led away to a scrub-

ber of any desired means of purification and treatment.

The thermostats may be set as desired according to the particular fractions that it is desired to condense, and if the thermostats 96, 99 and 100 are set for 518°, 446°, and 338° F. respectively, then the chambers 87, 88, 89 and 90 will condense the anthracene, creosote, carbolic and benzene fractions respectively. These will be substantially pure and require little treatment before use. Each tank will be provided with any appropriate means for drawing off the products of condensation. If desired the thermostats may be made double acting and may control valves which regulate the admission of normal steam to the chambers, so that both limits of temperature can be accurately determined. Furthermore, if desired, a thermostat may be placed at the bend where the condenser column leaves the benzene group and control the admission of cooling water to the tank 102 and coil 101. This should be set just below the condensation point of benzene and will cause considerable free ammonia gas to be liberated which can be collected in any desired manner.

As shown in figures 4 and 5, the withdrawal cylinders 61 have a series of pockets 10 formed by partitions 61^a extending radially from the central hub, and these partitions have serrated edges which cooperate with the apron 68 and the casing 67 to break up the coal before delivery to the worm conveyor.

The steam coils in the condensing chambers 87, 88 and 89 may be arranged as shown in Figure 11. The coils are supported at their inner end by a cross piece 103 provided with wheels 104 that run on the bottom of the chamber. The outlet and inlet ends of the coil pass through a flanged plate 105 which is larger than the opening in the side of the chamber which it covers and is bolted to the chamber. To remove any coil, it is therefore only necessary to release these bolts, disconnect the coil from the pipes, and remove the whole device shown in Figure 11 as a unit.

As already stated, a similar flanged plate 50 may be adopted for the support and removal of the agitators and withdrawal cylinders.

The illustration is in many respects diagrammatic, since it is obvious that many changes in size, form and arrangement of parts may be made without departing from the spirit of the invention which is to be regarded as limited only by the scope of the appended claims.

I claim as my invention:

1. Apparatus for the distillation of coal comprising a retort, means for supplying coal thereto continuously, a plurality of pipes within the retort for admitting superheated steam in the form of jets, a plural-

ity of agitators within the retort, withdrawal cylinders and a conveyor for continuously withdrawing the treated coal.

2. A retort for the non-destructive distillation of coal comprising a sectional casing, an inlet for the supply of coal, a plurality of pipes for the supply of superheated steam, a water supply pipe, rotating agitators for the mass of coal being treated, withdrawal cylinders, and a conveyor to which the treated coal is transferred by said withdrawal cylinders.

3. A retort for the non-destructive distillation of coal comprising a casing, an inlet for the supply of coal, a plurality of superheated steam jets within the retort, rotating agitators for the mass of coal being treated, rotating cylinders containing pockets, and a conveyor receiving the treated coal from said cylinders.

4. A retort for the non-destructive distillation of coal comprising a casing closed against the ingress of air, an inlet through which the coal is supplied together with superheated steam, pipes within the retort for the supply of superheated steam to the coal being treated, rotary agitators for the mass of coal being treated, rotary withdrawal cylinders, means for rotating the agitators and cylinders, and a conveyor receiving the treated coal from said cylinders and delivering it to the exterior of the retort.

5. In an apparatus for the distillation of coal which comprises a retort, withdrawal cylinders rotating on different axes within said retort, each of said cylinders being provided with pockets having serrated edges, an apron closely overlying said cylinders and cooperating with the serrated edges to crush the mass of coal before withdrawal, and means for rotating said cylinders.

6. Apparatus for the distillation of coal comprising a retort, an endless drag conveyor for supplying coal thereto, means for preheating the conveyor, means for supplying steam to the inlet thereof to displace indrawn air, and means for supplying jets of steam to the conveyor near the outlet to clean the same and aid in the movement of the coal.

7. Apparatus for the distillation of coal comprising a retort, an endless drag conveyor for supplying coal thereto, an inlet and an outlet for said conveyor, means for preheating said conveyor, means for supplying steam to the inlet thereof to displace indrawn air, means for supplying jets of steam downwardly directed against the conveyor near the outlet to clean the conveyor and aid in the movement of coal therefrom.

8. In apparatus for the distillation of coal which comprises a retort, a drag conveyor

for delivering coal thereto which comprises a sectional casing having a central and two end sections, an endless conveyor running about wheels located in the end sections, and 5 a steam jacket for the central section.

9. In an apparatus for the distillation of coal which comprises a retort, a drag conveyor for delivering coal thereto which comprises a sectional casing having a central and two end sections, an endless conveyor therein, a wheel rotating about a fixed axis supporting the conveyor and another wheel rotating in movable bearings also supporting the conveyor. 10

15 10. Apparatus for the distillation of coal comprising a retort formed of a plurality

of sections, steam pipes carried by one of said sections, agitators carried by another of said sections, and withdrawal cylinders carried by another of said sections. 20

11. Apparatus for the distillation of coal comprising a retort formed of a plurality of sections, steam pipes carried by one of said sections, agitators carried by another of said sections, withdrawal cylinders carried by another of said sections, and means for driving said agitators and withdrawal cylinders simultaneously. 25

In testimony whereof, I have hereunto subscribed my name.

JAMES T. FENTON.
